INTERNAL COMBUSTION ENGINE

Filed April 15, 1929

Inventor
RUDOLPH WEHR

By Fred D. Taylor

Attorney

UNITED STATES PATENT OFFICE

RUDOLPH WEHR, OF LOS ANGELES, CALIFORNIA, ASSIGNOR TO THE WEHR MOTOR COMPANY, A CORPORATION OF CALIFORNIA

INTERNAL-COMBUSTION ENGINE

Application filed April 15, 1929. Serial No. 355,060.

My invention relates to internal combustion engines, in which a means is provided for compensating for the destructive effect of the shocks or blows caused by the explosion of the charge acting on the piston of said engine.

It accordingly is an object of my invention to provide a novel form of internal combustion engine in which the cylinder thereof is provided with a chamber in which the mixture is adapted to be exploded, the exploded charge being crowded between the top of said piston and the lower part of the valve casing of said engine, preferably in constricted spaces to neutralize or compensate for the destructive effect of the shocks or blows received by said piston when the mixture is exploded.

A further object of my invention is to provide a novel form of cylinder and piston construction adapted to be associated with internal combustion engines, the cylinder of which has an enlarged chamber in which the mixture is to be exploded; said piston having a projection adapted to extend into the cylinder port so that when said mixture is exploded the charge will be crowded into a smaller but progressively enlarging space to compensate for the destructive shocks or blows produced by the exploded mixture.

The above and further objects and advantages of my invention as will hereinafter more fully appear, I attain by the structure disclosed in the specification and illustrated on the drawings forming a part of my application.

Reference is had to the accompanying drawings, in which similar reference characters denote similar parts. In the drawings,

Fig. 1 is a fragmentary transverse cross-sectional view of an internal combustion engine provided with my invention, and

Fig. 2 is a top plan view of the piston.

Describing my invention more in detail, in its broader aspects said invention comprises a cylinder equipped with an enlarged space or chamber in which the mixture is to be exploded, the end of the piston acted upon by the explosive force of the exploded mixture being adapted to coact with said chamber to

form a set of constricted spaces of smaller volume than said chamber so that the exploded mixture may be crowded therein to neutralize or compensate the destructive effect of the shocks or blows caused by the explosion of the mixture.

More specifically, my invention comprises an engine equipped with any preferred number of cylinders 2 having an enlarged end 4, which, with the bottom 6 of the valve casing 8 forms a chamber 10 in which the mixture is adapted to be exploded, a spark plug 12 being provided for this purpose.

The valve casing 8 is provided with the usual inlet and exhaust ports 14 and 16, controlled by the rotary valve 18, it being of course understood that in practice any other forms of valve or valves desired may be used.

The piston 20 is of usual form, except that it is provided with a projection 22, extending across the top thereof, either hollow as shown, or solid, which projection is adapted periodically to extend into the cylinder port 24 when the piston is at the extreme end of its stroke, a suitable clearance space of smaller volume than that of the chamber 10 being provided between the end of said piston, the projection 22, the bottom 6 of the valve casing 8 and the valve 18 closing the cylinder port 24.

The mixture, on the suction stroke of the piston 20, having been drawn into the chamber 10 of the cylinder 2 through the intake port 14 and the cylinder port 24, the valve 18 being properly positioned to provide for the same, said charge is compressed in the chamber 10 by the compression stroke of the piston, said charge being confined within the larger space in said chamber, after which said charge is ignited by the plug 12.

As will be clear, the effect of the explosion is not directly communicated to the fluid effective end of the piston 20, but on the contrary is crowded in between the smaller space between said piston, the part 6 of the valve casing and in the clearance spaces between the projection 22 and the valve 18 as said projection is positioned in the cylinder port 24, forming a set of constricted spaces which are progressively enlarged as the charge explodes, thus neutralizing or compensating for

the destructive shocks or blows of the explosion reducing their effect to a minimum.

While I have thus described my invention with great particularity, it will be clear that the same may be modified throughout a wide range. I accordingly do not propose to be limited to the exact details of construction described and claimed but reserve the right in practice to make any and all modifications that fall within the scope of the appended claims.

I claim as my invention:

1. In an internal combustion engine including a cylinder, a piston operable therein, and a valve casing, of a chamber formed by said valve casing and an enlarged portion on said cylinder, said chamber being adapted to receive the explosive charge introduced therein and coact with said piston to constrict the exploded charge so that the shock of its explosive force will be compensated.
2. In an internal combustion engine including a cylinder, a piston operable therein, and a valve casing, of a chamber formed by said valve casing and an enlarged portion of said cylinder, said valve casing being provided with a port, ignition means associated with said chamber, and means associated with said piston and adapted to be projected into said port, whereby, when the mixture introduced in said chamber is ignited, the exploded mixture will be crowded into clearance spaces above said piston, to compensate for the shock of said explosion.
3. In an internal combustion engine including a cylinder, a piston operable therein, a ported valve casing associated with said cylinder, a valve in said valve casing, of means associated with said cylinder and said valve casing adapted to coact with said piston, said valve, and said valve casing, whereby the exploded mixture will be confined in clearance spaces so that the force of said exploded mixture will be compensated.
45. In testimony whereof I have signed my name to this specification.

RUDOLPH WEHR.
